Primary Examiner — Michael C Stout*Assistant Examiner* — Melvin L Davis(74) *Attorney, Agent, or Firm* — ScienBiziP, P.C.(57) **CLAIM**

The ornamental design for a weight bench, as shown and described.

DESCRIPTION

FIG. 1 is a front perspective view of a weight bench, showing our design.

FIG. 2 is a rear perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a perspective view of the weight bench of FIG. 1 wherein a bench is up forward.

FIG. 10 is a perspective view of the weight bench folded up; and,

FIG. 11 is an enlarged view of an area labeled 11 in FIG. 1. The dot-dash boundary line demarcates an enlargement of a portion in FIGS. 1 and 11 that form no part of the claimed design.
